Inventor

Walter W. Crate.

UNITED STATES PATENT OFFICE.

WALTER W. CRATE, OF CAMDEN, NEW JERSEY.

ARTIFICIAL TOOTH.

1,246,060.

Specification of Letters Patent. Patented Nov. 13, 1917.

Application filed November 25, 1916. Serial No. 133,353.

To all whom it may concern:

Be it known that I, WALTER W. CRATE, a citizen of the United States, and a resident of the city of Camden, in the county of 5 Camden, State of New Jersey, have invented certain new and useful Improvements in Artificial Teeth and Methods of Manufacture, of which the following is a specification.

10 My invention relates to improvements in artificial teeth, the object of the invention being to provide an improved anchorage for the tooth which is accomplished by so constructing the tooth as to provide at the back thereof a plurality of anchoring means independent of each other, and at least one of said anchoring means constituting a hole or recess located at the back of the tooth and having its wall at an angle to the other anchoring means and at an acute angle to the back face of the tooth, whereby when the material to which the tooth is attached, is forced into the hole or recess, a secure anchorage is effected.

15 A further object is to provide an artificial tooth having anchoring means at its middle strongest portion and so arranged as to insure a proper attachment of the tooth to its support without disfiguring the 20 tooth or materially weakening the same.

25 With these and other objects in view the invention consists in certain novel features of construction and combinations and arrangements of parts as will be more fully 30 hereinafter described and pointed out in the claims.

In the accompanying drawings:

35 Figure 1 is a plan view of the inner surface of one mold section showing the arrangement of cores seated in the holes in the mold, with a metal pin seated in a hole in the center of the mold, ready for placing of tooth material.

40 Fig. 2 is a view in section through the completed mold with the tooth therein, the section being taken on the line 2-2 of Fig. 1, and

45 Figs. 3, 4, 5 and 6 are plan views or rear elevations of various forms of teeth embodying my invention.

50 1 and 2 represent the two sections of the mold. Mold section 1 is provided with four recesses 4^a supporting four cores 4, the ends in the recesses being marked 4^b. Section 1 also supports the usual anchoring pin 7, the

end thereof in the mold section being indicated by the reference numeral 7^a.

The ends 4^b of the cores 4 extend into the tooth, 5 and section 1 is provided with an outlet 4^d for each core 4, so that the latter 60 when molten from the heat of baking the tooth can run out, leaving a hole or recess 4^c in the tooth.

The core-pins 4 are therefore of a material which will melt under the necessary 65 temperature.

While I have described one method of forming holes or recesses 4^c in a tooth, I would have it understood that these holes or recesses may be made in other ways, and 70 I do not limit myself in this particular.

In Fig. 3 I show a tooth provided at the center of its back with an anchoring pin 7^a and with four anchoring holes or recesses 4^a, all located within the strongest portion 75 of the tooth, indicated by the line 11.

In Fig. 4, I omit the pin 7 and provide a hole or recess 6.

Fig. 5 shows a tooth having recessed edges 13, and a tooth such as here shown may be 80 molded, and anchoring means provided therein such as contemplated by my invention after the tooth is completely formed.

Fig. 6 shows a tooth having a plurality of holes or recesses of various shapes having their walls at an angle to each other and at an acute angle to the back face of the tooth. The different holes or recesses in Fig. 6 are given the reference numerals 6, 10, and 12 and 8 respectively, and the 90 inclined walls thereof are indicated by the reference numerals 6^a, 10^a, 12^a, and 8^a respectively.

In all forms of my invention, I provide a tooth at the middle section of its back 95 with a plurality of independent anchoring means. One of these anchoring means may consist of an ordinary pin 7, but in any event one of the anchoring means will consist of a hole or recess independent of the other anchoring means, and having its walls at an angle to the other anchoring means, and at an acute angle to the back face of the tooth, so that the material of the support will project into the hole or recess and 100 form an effectual anchorage, preventing any possibility of accidental removal.

Various slight changes might be made in the general form and arrangement of parts described without departing from my in- 110

vention, and hence I do not limit myself to the precise details set forth, but consider myself at liberty to make such changes and alterations as fairly fall within the spirit and scope of the appended claims.

Having fully described my invention, what I claim as new and desire to secure by Letters Patent is:

1. An artificial tooth, having a pin per-

pendicular to the back of the tooth, and a recess at an angle to the pin and to the back of the tooth.

2. An artificial tooth, having a pin located centrally at the back of the tooth, and having a recess at each corner of the back of the tooth located at an angle to the central pin and to the back of the tooth.

WALTER W. CRATE.

Copies of this patent may be obtained for five cents each, by addressing the "Commissioner of Patents, Washington, D. C."
